CLAIM

I claim the ornamental design for a for a curtain rod support assembly, as shown.

DESCRIPTION

FIG. 1 shows a top perspective view of a curtain rod support assembly showing my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a left side elevational view thereof; and,

FIG. 7 is a right side elevational view thereof.
